[57] CLAIM

The ornamental design for a storage box for motorcycles, as shown.

DESCRIPTION

FIG. 1 is a view in perspective as seen from the rear, side and top of the storage box for motorcycles showing my new design.

FIG. 2 is a view in side elevation thereof, the side opposite that shown being a mirror image.

FIG. 3 is a view in top plan thereof.

FIG. 4 is a view in front elevation thereof.
